[57] CLAIM

The ornamental design for a front face segment of a vehicle wheel, as shown and described.

DESCRIPTION

FIG. 1 is a front perspective view of a front face segment of a vehicle wheel showing my new design; and, FIG. 2 is a front elevational view thereof.

The broken lines shown in FIG. 1 of the drawings are for illustrative purposes only and the subject matter depicted thereby constitutes no part of the claimed design.

FIG. 1

FIG. 2
